PRESS UNIT DRIVE

Henry A. Wise Wood, New York, N. Y., assignor
to Wood Newspaper Machinery Corporation,
New York, N. Y., a Corporation of Virginia

Application February 9, 1931. Serial No. 514,375

3 Claims. (Cl. 101—220)

This invention relates to the drive of a printing press.

The principal object of the invention is to provide a drive in which the driving motor is located where it will take up no space beneath the press floor and no head room above the press unit and no floor space elsewhere. The invention has for its secondary object the driving of the press from a motor in as close proximity as possible to the cylinder of the press which it drives, thus avoiding a comparatively long transmission of power.

Other objects and advantages of the invention will appear hereinafter.

Reference is to be had to the accompanying drawing, in which

Fig. 1 is a side view, partly in section, of the printing couples of a printing press, showing the drive arranged in accordance with this invention, and

Fig. 2 is a similar view showing a modification of the means for transmitting power from the motor to the cylinder.

The saving of space in a press room is becoming more and more important as printing presses are enlarged and attempts are made to put the enlarged presses in the same spaces occupied by the old ones. It is necessary therefore to avoid the taking up of additional floor space by the motor and also these presses are being made so tall that it is important to save the head room occupied by a motor located at the top of a press. Even the room required beneath the press floor for a motor when placed below the press is disadvantageous. By this invention, the employment of room in the places indicated is avoided.

In the form shown in Fig. 1, the press unit is arranged in such a way that the driving motor 10 is attached to a brace 11 of the press frame and is firmly supported thereby. It is located inside the press under the printing couples and between the inking mechanisms where it is as closed as possible to the first impression cylinder 12 which it drives directly. This drive, in the form shown in this figure, is by a chain 13 and sprockets on the motor shaft and the cylinder shaft. The rest of the unit is driven in any desired way by gear or chain connections from the first impression cylinder.

As stated, the motor is located close to the first impression cylinder 12 and between the two inking mechanisms 14 in a space not heretofore occupied. This arrangement provides for the utilization of this previously wasted space and avoids the necessity of mounting the motor

overhead or underneath or on the floor which supports the press. The drive is direct and avoids the employment of shafts between the motor and the impression cylinder as well as excess transmission means, thereby simplifying the mechanism. This permits of the construction of a very compact press unit which may be placed in a relatively small space.

Each unit is driven with a separate motor. All of the motors of the combination are held in synchronism to keep the papers properly registered.

In the form shown in Fig. 2, everything said above applies. The drive from the motor 10 to the cylinder 12 is by means of gearing 16 which makes the construction equally compact and gives the same advantages.

Although I have illustrated and described only two forms of the invention, I am aware of the fact that other modifications can be made therein by any person skilled in the art without departing from the scope of the invention as expressed in the claims.

Therefore I do not wish to be limited in this respect, but what I do claim is:

1. In a printing press unit, the combination with the printing couples of a motor for operating the press located inside the press immediately beneath the printing couples, and means for driving one of the cylinders of the printing couples directly from the motor.

2. In a printing press unit, the combination of the printing couples and inking mechanism located below the printing cylinders, of a motor located inside the press in the space between the inking mechanisms and connected directly with one of the cylinders for driving the entire unit.

3. In a printing press unit, the combination with a frame on which the parts are supported and a cross brace inside the press constituting a part of that frame located directly under the impression cylinders, of a driving motor for one of said impression cylinders supported by said cross brace.

HENRY A. WISE WOOD.
